US0D1033463S

(12) **United States Design Patent** (10) **Patent No.:** **US D1,033,463 S**
(45) **Date of Patent:** **** Jul. 2, 2024**

(54) **DISPLAY SCREEN OR PORTION THEREOF
WITH GRAPHICAL USER INTERFACE**

(71) Applicant: **Roche Diabetes Care, Inc.**,
Indianapolis, IN (US)

(72) Inventors: **Guillermo Martinez Lopez-Corell**,
Vienna (AT); **Oleg Novikov**, Vienna
(AT)

(**) Term: **15 Years**

(21) Appl. No.: **29/876,055**

(22) Filed: **May 16, 2023**

(57) **CLAIM**

The ornamental design for a display screen or portion
thereof with graphical user interface, as shown and
described.

DESCRIPTION

The patent or application file contains a least one drawing
executed in color. Copies of this patent or patent application
publication with color drawing(s) will be provided by the
Office upon request and payment of the necessary fee.

FIG. 1 is a front view of a display screen or portion thereof
with graphical user interface showing our design in an
embodiment;

FIG. 2 is a front view of a display screen or portion thereof
with graphical user interface showing our new design in a
second embodiment; and,

FIG. 3 is a front view of a display screen or portion thereof
with graphical user interface showing our new design in a
third embodiment.

The broken lines illustrate a display screen or portion
thereof, and form no part of the claimed design.
